UNITED STATES PATENT OFFICE.

CHARLES W. KECKLER, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,324,355.

Specification of Letters Patent.

Patented Dec. 9, 1919.

Application filed September 22, 1916. Serial No. 121,570.

To all whom it may concern:

Be it known that I, CHARLES W. KECKLER, a citizen of the United States, residing at Newark, in the county of Essex and State 5 of New Jersey, have invented certain new and useful Improvements in Telephone-Exchange Systems, of which the following is a full, clear, concise, and exact description.

This invention relates to telephone 10 exchange systems, and more particularly to such systems of the central energy type in which telephone lines terminating at the same or different telephone exchanges may be interconnected by means of link or connecting circuits.

The object of this invention is the production of such a system by means of which the work of establishing connections between telephone lines may be greatly simplified.

20 In accordance with one feature of this invention, a link circuit employed in establishing connections between telephone lines has associated therewith apparatus, controlled by the connection of the answering end of 25 the link circuit with a telephone line or by a listening key coöperating with apparatus, operating upon the connection of the calling end with another line, to control the application of ringing current to the called telephone line.

In accordance with another feature of this invention, apparatus associated with a connecting circuit prevents the connection of an operator's telephone set with the talking 35 strands thereof while the telephone lines are joined thereby for conversation, but which permits such connection after the party on one of the lines has made a recall.

In accordance with still another feature of 40 this invention, apparatus associated with connecting circuits joining telephone lines terminating in different telephone exchanges operates, upon the abandonment of the call by the calling party, to disconnect a source 45 of ringing current from the called telephone line; provided the called party has not previously responded.

In accordance with the fourth feature of 50 this invention, there is provided apparatus which functions to furnish a busy signal when testing a busy line with a link circuit to the tip conductor of which is connected a source of current.

For a more complete understanding of this 55 invention reference should be had to the

following description taken in connection with the drawings, wherein:

Figure 1 shows a telephone line and a cord circuit, the latter embodying certain features of this invention; and

Fig. 2 shows a trunk circuit and a telephone line, the former operating with the cord circuit shown in Fig. 1 and embodying certain other features of this invention.

Referring to the drawings, there are 60 shown two telephone lines A and B, the former terminating at one central office, and the latter at a second central office. At the first central office there is a cord circuit C used for interconnecting telephone lines 70 similar to A and B, it being understood that a plurality of such lines terminate at the first central office. This cord circuit C may also be used to connect a telephone line such as A with a trunk circuit D extending from the 75 first to the second central office, the trunk circuit D being adapted to connect at its other end with another telephone line, such as B.

Assuming that subscriber A wishes to 80 converse with subscriber B, A removes the receiver from the switchhook causing the operation of line relay 5 over a circuit from battery, through the winding of line relay 5, right-hand winding of cut-off relay 6, 85 normal contact thereof, out over A's line, through the apparatus at the station, back over the other line, and through the left-hand winding of cut-off relay 6 to ground. Line relay 5, in operating, causes line lamp 90 7 to light. Cut-off relay 6, however, is differentially wound so that it does not operate upon the completion of the circuit above traced. The operator observing the lighted condition of line lamp 7 inserts the answering plug of cord circuit C into the jack associated with A's line, thereby causing the operation of relay 8 and cut-off relay 6 over a circuit from battery, through winding of relay 8, tip conductors of the answering plug and jack and the left-hand winding of cut-off relay 6 to ground. Cut-off 95 relay 6, in operating, connects the sleeve of the jack with the ring thereof and causes the line lamp 7 to be extinguished. Relay 100 8, in operating, causes the operation of relay 9 over a circuit from battery, through the right-hand contact of relay 8, normal contact of relay 10, normal contact and winding of relay 9, and lower normal contact of 105

110

relay 11 to ground. Relay 9, in operating, completes a locking circuit for itself by way of its left-hand alternate contact. Relay 12 now operates over a circuit which 5 may be traced from battery, through the right-hand contact of relay 8, winding of relay 12, ring contacts of the plug and jack, over one side of the line, through the station apparatus, back over the other side of 10 the line, and the left-hand winding of cut-off relay 6 to ground. Relay 12, in operating, causes the operation of relay 10 thereby preventing the lighting of the answering 15 supervisory lamp 13. Relay 12, in operating, also causes the operation of a slow-release relay 14.

The operator may now actuate listening-key 20, thereby causing the operation of relay 11 over a circuit from battery, through 20 the winding of relay 11, upper contact of listening-key 20, middle alternate contact of relay 9 or normal contact of relay 32 to ground. Relay 11, in operating, connects an operator's telephone set to the talking 25 strands of the cord circuit C, completes a locking circuit for itself through its lower alternate contact and releases relay 9. In this connection it is to be noted that if listening-key 20 is not actuated before the 30 operation of relay 10, the answering supervisory lamp 13 will be lighted intermittently over a circuit from battery, through interrupter 21, right-hand alternate contact of relay 9, alternate contact of relay 10 and 35 lamp 13 to ground. If this supervisory lamp is flashing when the listening-key is actuated, the release of relay 9 discontinues the flashing of the lamp because the right-hand alternate contact of relay 9 is now 40 open.

The operator, finding that subscriber B, whose line terminates at another central office, is desired, communicates with the operator at the second central office by 45 means of an order wire circuit (not shown) and receives a trunk assignment. Assuming that the trunk circuit D has been assigned, the operator restores listening-key 20 to normal position, releasing relay 11, 50 and inserts the calling plug of cord circuit C into the jack of trunk circuit D, thereby causing the operation of relays 23 and 26 over a circuit from battery, through the windings of relays 27 and 25, the lower 55 normal contact of relay 28, upper normal contact of relay 11, tip contacts of the calling plug and jack, and the winding of relay 26 to ground. Relay 27 is marginal and does not operate when the calling plug is 60 connected with the jack of a trunk circuit, but does operate when connected with the jack of a telephone line similar to A and B. Relay 25, in operating, causes the lighting of calling supervisory lamp 36 over a circuit from battery, through the lower alter- 65

nate contact of relay 25, lamp 36 and contact of relay 32 to ground. This lamp remains lighted until B removes the receiver from the switchhook. Relay 26, in operating, causes the operation of a slow-release relay 29, which, in operating, causes the operation of relays 30 and 31 over a circuit from battery, through the alternate contact of relay 12, left-hand alternate contact of relay 14, winding of relay 32, upper 70 normal contact of relay 28, ring contacts of the calling plug and jack, a winding of repeating coil 33, both windings of relay 30, another winding of repeating coil 33, winding of relay 31 and the contact of relay 29 to ground. The two windings of relay 30 are of high resistance preferably, approximately 12,000 ohms, so that relay 32, which is marginal, does not operate when in series with both windings of relay 30, 75 but does operate when one winding of relay 30 is short-circuited as will hereinafter more fully appear. The operation of relay 30 causes the lighting of lamp 34 over a circuit from battery, through the alternate contact of relay 30, lower normal contact of relay 35, lamp 34 and the normal contact of relay 40 to ground. 80

The operator at the second central office, before whom the lamp 34 is located, observes the lighted condition thereof and knows that the operator at the other central office has connected with the right trunk circuit, and tests line B. Assuming B's line to be busy, there will exist at the sleeve contacts of the jacks, a potential resulting from the connection of the sleeve contacts of one of the jacks with the live pole of battery, either by way of the calling or answering plug of a cord circuit or by way of the plug of a trunk 95 circuit. This potential will be sufficiently above that of the point 72 between resistances 45 and 70, so that upon the engagement of the tip of the plug of the trunk circuit with the sleeve contact of the jack, current will flow from the sleeve contact of the jack, through the tip of the plug, right-hand winding of relay 42, normal contact of relay 47, windings of polarized relays 41 and 46, and resistance 70 to ground. Relays 41 and 100 46 are oppositely poled, and relay 46 operates when its winding is traversed by current flowing in the direction just traced. Relay 46, in operating, closes its contact connecting battery in circuit with a winding 105 71 of an induction coil in the operator's telephone set, whereupon a click is heard in the operator's receiver.

If line B is not busy, the operator inserts the plug of the trunk circuit D into the jack 110 of B's line, thereby causing the operation of polarized relay 41, relay 42, and cut-off relay 43 over a circuit from battery, through contact 44 (which is located in the operator's jack and is closed whenever the operator's 115

plug is in the jack), resistance 45, windings of polarized relays 46 and 41 (these relays are poled oppositely), normal contact of slow-release relay 47, right-hand winding of relay 42, tip contacts of the plug and jack and the right-hand winding of cut-off relay 43 to ground. Polarized relay 41, in operating, causes the operation of slow-release relay 48 over a circuit from battery, through the contact of polarized relay 41, upper normal contact of relay 35, contact of relay 42 and the winding of relay 48 to ground. Relay 48, in operating, causes the operation of relay 35 and slow-release relay 47 over a circuit from battery, through the contact of relay 48, winding of relay 35, left-hand contact of relay 49, contact of relay 55, and the winding of slow-release relay 47 to ground. The operation of relay 35 establishes a locking circuit for relay 42 which may be traced from battery, through the upper alternate contact of relay 35, left-hand winding of relay 42, tip contacts of the plug and jack, and right-hand winding of cut-off relay 43 to ground. Relays 35, 47 and 48 are now locked up under control of relay 42. Upon the operation of relay 35 lamp 34 is extinguished, and relay 56 and slow-release relay 40 operate over a circuit from battery, through the alternate contact of relay 30, lower alternate contact of relay 35, and the windings of relays 40 and 56 in parallel to ground. The operation of slow-release relay 40 prepares a circuit for the right-hand winding of relay 49. Relay 56, in operating, connects a source of ringing current 57 to B's line. The circuit therefor may be traced from source 57, through the winding of tripping relay 55, upper alternate contact of relay 56, ring contacts of the plug and jack, out over one side of the line, through the call bell at station B, back over the other side of line, tip contacts of the jack and plug, lower alternate contact of relay 56, resistance 58, through battery to ground. Subscriber B, in responding to the operation of the call bell, removes the receiver from the switchhook and causes the operation of relay 55 which opens a short circuit through the left-hand winding of relay 49, which thereupon operates and opens the circuit of relay 56, which releases and disconnects ringing current from B's line. Relay 49, in operating, is locked up in circuit with relays 35 and 47. Upon the release of relay 56, relay 59 operates over the line circuit, and, in operating, short-circuits the upper winding of relay 30, thereby permitting the operation of marginal relay 32. Marginal relay 32, in operating, extinguishes the calling supervisory lamp 36 in the cord circuit C.

After the completion of the conversation between subscribers A and B, both restore the receivers to the switchhooks, the restoration of the receiver at station A causing the release of relay 12, and in turn, relays 10 and 14. Upon the release of relay 10, answering supervisory lamp 13 is lighted to furnish a disconnect signal. Restoration of the receiver to the switchhook at station B causes the release of relay 59 which opens the short circuit of the upper winding of relay 30, thereby causing the release of marginal relay 32 whereupon the calling supervisory lamp 36 is lighted to furnish a disconnect signal. The operator at the first central office, observing the lighted condition of the disconnect signals 13 and 36, withdraws the answering and calling plugs from the jacks whereupon relay 30 in the trunk circuit D releases, and, in releasing, causes the release of relay 40, whereupon the lamp 34 is lighted over a circuit from battery, through the normal contact of relay 30, right-hand contact of relay 47, lamp 34 and normal contact of relay 40 to ground. The operator at the second central office, observing the lighted condition of the disconnect lamp 34, withdraws the plug of the trunk from the jack of B's line, whereupon all apparatus associated with both lines, the cord circuit and the trunk circuit is returned to normal condition.

It will be assumed that subscriber A has called for subscriber B, that the cord's circuit connects line A with the trunk circuit D, that the plug of trunk circuit D is connected with the jack of B's line, and that the call bell at subscriber B's station is being operated. Now suppose that before subscriber B responds, subscriber A abandons the call, in which case the restoration to the switchhook of the receiver by subscriber A causes the release of relay 12, thereby releasing relays 10 and 14, and lights the answering supervisory lamp 13. The release of relay 10 causes the operation of relay 9 over a circuit hereinbefore traced. During the time between the release of relay 12 and the release of slow-release relay 14, current is removed from the circuit including relays 30, 31 and 32. Relays 30 and 31 thereupon release momentarily or until slow-release relay 14 has completely released, whereupon the circuit including the relays 30, 31 and 32 is again established. Upon the momentary release of relay 30, relay 49 is operated over a circuit from battery, through the normal contact of relay 30, right-hand winding of relay 49, and alternate contact of slow-release relay 40 to ground. Relay 49, in operating, causes the release of relay 56 in the manner described in connection with the tripping of the ringing by the response of subscriber B. Relay 49, in operating, is locked up in circuit with relays 35 and 47 as before described. Relay 40 is, as before described, of the slow-releasing type, and is so made that it will not release, due to the momentary release of relay 30 and furnish

a disconnect signal by the lighting of lamp 34. Lamp 34 is not lighted at this time because the relay 40 fails to release, before the relay 30 is again energized upon the complete release of relay 14.

Should subscriber A, upon completion of the conversation, wish to attract the attention of the operator at the first central office to make a recall, or for any other purpose, restoration of the receiver to the switchhook, followed by the removal therefrom before the cord circuit C is disconnected from A's line, will cause the answering supervisory lamp 13 to be lighted intermittently to furnish a recall signal. This is accomplished in the following manner: Upon the restoration of the receiver at station A to the switchhook, relays 12, 10 and 14 release, and upon the release of relay 10, relay 9 operates and completes a locking circuit for itself as hereinbefore described. The subsequent energization of relay 12, followed by the energization of relay 10, due to the removal of the receiver from the switchhook at station A, includes the interrupter 21 in circuit with the lamp 13 and battery, whereupon the lamp is lighted intermittently. The operator at the first central office, observing the flashing of the supervisory lamp 13, may actuate listening-key 20, thereby causing the operation of relay 11, which, in operating, locks up and causes the release of relay 9 to stop the flashing of the supervisory lamp 13. The operator may now complete any desired connection for subscriber A.

It will now be assumed that subscriber A desired to be connected with a line terminating in the same central office. This line 40 is similar in all respects to lines A and B, and in the following description it will be supposed, for the sake of convenience, that line B terminates in the first central office. The operator, after inserting the answering 45 plug of cord circuit C into the jack of line A and having been advised by subscriber A that connection is desired with a line terminating in the same central office, for example, line B, restores listening-key 20 to 50 normal position, releasing relay 11, and inserts the calling plug of the cord circuit C into the jack of B's line, whereupon relays 27, 25 and 43 are operated over a circuit from battery, through the windings of relays 55 27 and 25, lower normal contact of relay 28, upper normal contact of relay 11, tip contacts of the plug and jack, and the right-hand winding of cut-off relay 43 to ground. The relay 25, in operating, lights 60 the calling supervisory lamp 36. The operation of relay 27 causes the operation of relay 28 over a circuit from battery through the contact of relay 27, winding of relay 28, contacts of relay 60 and 61, left-hand 65 contact of relay 8 and resistance 62 to

ground. Relay 28, in operating, completes a temporary locking circuit for relays 27 and 25 by way of the middle alternate contact of relay 28 and resistance 63 to ground. The opening of the lower normal contact 70 of relay 28 upon its operation thereby disconnects battery and relays 27 and 25 from the tip strands, and substitutes therefor battery through resistance 64, to prevent the possibility of the release of these relays due 75 to ringing current, as will hereinafter more fully appear. Relay 28, in operating, also connects a source of ringing current 65 to B's line through the winding of tripping relay 61, upper alternate contact of relay 28, ring contacts of the plug and jack, out over the one side of the line, through the call bell of station B, back over the other side of the line, tip contacts of the jack and plug, upper normal contact of relay 11, and alternate contact of relay 25 in parallel, lower alternate contact of relay 28 and resistance 64 through battery to ground. Subscriber B, in responding by the removal 85 of the receiver from the switchhook, causes 90 the operation of relay 61, which, in operating, removes the short-circuit from the left-hand winding of relay 60. Relay 60 now operates over a circuit from battery, through the contact of relay 27, winding of relay 95 28, left-hand winding of relay 60, left-hand contact of relay 8 and resistance 62 to ground. Relay 60, in operating, completes a locking circuit for itself from battery, through the lower alternate contact of relay 25, alternate contact of relay 60, left-hand winding thereof, left-hand contact of relay 8 and resistance 62 to ground, and establishes a short circuit for relay 28 which thereupon releases, disconnecting the ringing current from the line and again connecting battery to the tip strand of the cord circuit through the windings of relays 27 and 25. Relay 32 now operates over a circuit from battery through the alternate contact of relay 12, left-hand alternate contact of relay 14, winding of relay 32, upper normal contact of relay 28, ring contacts of the plug and jack, out over one side of the line, through the station apparatus, back 110 over the other side of line, and the right-hand winding of cut-off relay 43 to ground. The operation of relay 32 extinguishes calling supervisory lamp 36. At the completion 115 of conversation, subscribers A and B restore the receivers to the switchhooks, causing the release of relays 12, 10, 14 and 32, whereupon circuits are completed for the answering and calling supervisory lamps 13 and 36 which are thereby lighted to furnish 120 disconnect signals. The operator may now withdraw the plugs from the jacks, whereupon all apparatus is returned to normal.

If, for any reason, the operator at the first central office should wish to originate a 130

call on a telephone line, for example, line A, this may be done by the insertion of the calling plug of the cord circuit C into the jack of A's line, whereupon relays 27, 25 and 5 cut-off relay 6 operate over a circuit from battery, windings of relays 27 and 25, lower normal contact of relay 28, upper normal contact of relay 11, tip contacts of the calling plug and jack, and the left-hand 10 winding of cut-off relay 6 to ground. By the operation of relay 25 the upper alternate contact thereof is closed, completing a locking circuit for relays 27, 25 and 6, so that the subsequent operation of relay 11 will 15 have no effect upon these three relays. Relay 27, in operating, closes a contact in circuit with relay 28, but this relay 28 does not operate, for the circuit is not complete, it being open at the left-hand contact of relay 20 8, and at the lower contact of the listening-key 20 (which contacts are in parallel). Since the answering end of cord circuit C is not connected with a line, relay 28 cannot operate until the listening-key 20 is actuated. Upon the actuation of the listening-key, relay 28 operates over a circuit from battery, through the contact of relay 27, winding of relay 28, normal contacts of relays 60 and 61, lower contact of listening-key 20, and resistance 62 to ground. Upon 30 the operation of relay 28, ringing current is connected to A's line. Before the response of subscriber A, should the operator, for any reason, desire to discontinue ringing on this line, the restoration of the listening-key 20 to normal will bring about such a result. In this way the operator may employ a machine ringing cord circuit to originate a call on any line, and after ringing 35 thereon may discontinue such ringing and still hold the line so that upon the response of the signaled party, the calling supervisory lamp will be extinguished. This scheme permits the operator to signal the party, and while waiting for the response thereof, attend to the answering and completing of other calls.

What is claimed is:

1. A telephone exchange system comprising subscribers' lines, a link circuit connecting the lines, an operator's telephone set normally disconnected from the link circuit, a listening relay controlling the connection of the operator's telephone set to the link circuit, a second relay associated with the link circuit, an operating circuit for the second relay including a contact on the listening relay completed upon the restoration of the receiver to the switchhook at one of the connected stations, operator-controlled switching means, and an operating circuit for the listening relay jointly controlled by the second relay and the operator-controlled switching means.
2. A telephone exchange system comprising

ing subscribers' lines, a link circuit connecting the lines, an operator's telephone set normally disconnected from the link circuit, a listening relay for connecting the operator's telephone set to the link circuit, a second relay associated with the link circuit, an operating circuit including a contact of the listening relay completed upon the opening of the line circuit at the calling station, a manually operated switch, and an operating circuit for the listening relay closed by the energization of the second relay and the actuation of the switch.

3. A telephone exchange system comprising subscribers' lines, a link circuit connecting the lines, an operator's telephone set normally disconnected from the link circuit, a listening relay for connecting the operator's telephone set to the link circuit, a supervisory relay associated with the answering end of the link circuit, a third relay, an operating circuit therefor including a contact of the listening relay completed upon the deenergization of the supervisory relay, a manually operated switch, and an operating circuit for the listening relay closed by the energization of the third relay and the actuation of the switch.

4. A telephone exchange system comprising telephone lines, a link circuit, an operator's telephone set, a listening key controlling the connection of the operator's telephone set to the link circuit, a source of ringing current, a relay for connecting said source to a line, and an operating circuit for said relay controlled jointly by said listening key and the connection of said link circuit with a line independent of the connection of the link circuit with any other line.

5. A telephone exchange system comprising telephone lines, a link circuit, a source of ringing current, a relay for connecting said source to a line, and an operating circuit for said relay jointly controlled by the connection of the ends of the link circuit with telephone lines, independent of the condition of the substation apparatus associated with said lines.

6. A telephone exchange system comprising telephone lines, a link circuit, an operator's telephone set, a listening key controlling the connection of the operator's telephone set to the link circuit, a source of ringing current, and a relay for connecting said source to a called line jointly controlled by the connection of the answering end of the link circuit with a line or the actuation of the listening key and the connection of the calling end of the link circuit with the called line.

7. A telephone exchange system comprising a telephone line terminating in a plurality of sets of terminals, a test terminal for each set normally free from battery and

ground connections, a connecting circuit, a cut-off relay for each line actuated upon connection of the connecting circuit with a set of the terminals to connect a source of potential to the test terminals, a second connecting circuit, an operator's receiver, and a polarized relay responsive to the engagement of the second connecting circuit with

a test terminal of a busy line, and a circuit completed by the operation of the polarized relay to produce a click in the operator's receiver.

In witness whereof, I hereunto subscribe my name this 19th day of September, A. D. 1916.

CHARLES W. KECKLER.
